CLAIM

The ornamental design for a connector joint, as shown and described.

DESCRIPTION

FIG. 1 is a perspective exploded view of a connector joint showing a first embodiment of our new design.

FIG. 2 is a front view of the connector joint of FIG. 1.

FIG. 3 is a back view of the connector joint of FIG. 1.

FIG. 4 is a top view of the connector joint of FIG. 1.

FIG. 5 is a bottom view of the connector joint of FIG. 1.

FIG. 6 is a perspective exploded view of a connector joint showing a second embodiment of our new design.

FIG. 7 is a front view of the connector joint of FIG. 6.

FIG. 8 is a back view of the connector joint of FIG. 6.

FIG. 9 is a top view of the connector joint of FIG. 6; and,

FIG. 10 is a bottom view of the connector joint of FIG. 6. The broken line portion of the figures is included to show unclaimed subject matter only and forms no part of the claimed design.

1 Claim, 6 Drawing Sheets
